(57) **CLAIM**

The ornamental design for a fishing jig with moulded outer shell and parting line, as shown and described.

DESCRIPTION

FIG. 1 is a perspective view of a fishing jig lure with moulded outer shell and parting line showing the design of the invention.

FIG. 2 is another perspective view thereof.

FIG. 3 is a front view thereof.

FIG. 4 is a rear view thereof.

FIG. 5 is a bottom view thereof.

FIG. 6 is a top view thereof.

FIG. 7 is a side view thereof.

FIG. 8 is an opposite side view thereof.

FIG. 9 is a perspective view of an alternate embodiment of the fishing jig lure with moulded outer shell and parting line, showing the design of the invention.

FIG. 10 is another perspective view thereof.

FIG. 11 is a front view thereof.

FIG. 12 is a rear view thereof.

FIG. 13 is a bottom view thereof.

FIG. 14 is a top view thereof.

FIG. 15 is a side view thereof; and,

FIG. 16 is an opposite side view thereof.

The broken line showing of structural features in this figure and all following figures is included for the purpose of illustrating non-claimed subject matter and forms no part of the claimed design.
